UNITED STATES PATENT OFFICE.

JOHN H. PALMER, OF JERSEY CITY, NEW JERSEY.

SELF-FEEDING PEN.

1,198,950.

Specification of Letters Patent. Patented Sept. 19, 1916.

Application filed January 19, 1915. Serial No. 3,120.

To all whom it may concern:

Be it known that I, JOHN H. PALMER, a citizen of the United States, residing at Jersey City, in the county of Hudson and State of New Jersey, have invented certain new and useful Improvements in Self-Feeding Pens; and I do hereby declare the following to be a full, clear, and exact description of the invention, such as will enable others skilled in the art to which it appertains to make and use the same.

This invention relates to self feeding pens, and one of the principal objects of the invention is to provide a pen having a cap or reservoir provided with a compressible bulb or container for the ink, and a tube leading from the container to near the point or points of the pen, and means being provided for compressing the bulb, or for reducing the pressure therefrom to either feed the ink to the points of the pen or for filling the bulb.

Another object of the invention is to provide a compressible ink reservoir having a tube leading to near the point or points of the pen and a plug or button connected to the end of the barrel of the pen and slidably therein to operate the compressing device for bearing against the reservoir for expelling ink through the tube.

The foregoing and other objects may be attained by means of the construction illustrated in the accompanying drawings, in which—

Fig. 1 is a side elevation of a drafting pen made in accordance with this invention, Fig. 2 is a longitudinal sectional view of the same, Fig. 3 is a transverse sectional view taken on the line 3—3 of Fig. 2, looking in the direction indicated by the arrows, and Fig. 4 is a side elevation of the compressor for expelling the ink from the ink reservoir.

Referring to the drawing, the numeral 1 designates the barrel or casing of the pen, said barrel having a reduced and screw threaded lower end 2, said reduced end being solid and provided with a plain unthreaded bore 3. Fitted to the reduced end 2 is an interiorly screw threaded section 4 having a partition 5 therein provided with a bore which registers with the bore 3 in the reduced portion 2. The connection 4 is provided with an interiorly screw threaded portion 6 below the partition 5, and fitted in this screw threaded portion is a reduced

and threaded portion 7 formed integral with the pen point.

As shown in the drawing, the pen points 8 and 9 are of the type used by draftsmen and the plug 7 is provided with a plain opening 10 which registers with the opening in the partition 5 and the bore in the reduced portion 2. As is usual in pens of this character, there is a spring portion 11 to one of the points of the pen, and the points are adjustable toward and from one another by means of an adjusting screw 12.

Disposed in the barrel 1 is an ink reservoir A composed of some compressible material and made in the form of an elongated bulb, as shown in Fig. 2 of the drawing. The ink reservoir is hollow and connected to the lower end thereof is a tube a which extends through the bore in the reduced portion 2 through the bore in the partition 5, and through the opening 10 in the solid portion 7 of the pen points, said tube terminating at b near the points c of the pen. The feed tube a may have a contracted 80 opening at the end b.

A flat strip of spring metal is located within and extends longitudinally of the barrel 1. This strip has its ends offset to provide a compression member 14 and attaching members 14^a and 14^b. The attaching member 14^a is secured to the barrel 1 by a pin 13, and the attaching member 14^b is secured to a plug or button 15 slidably mounted in the outer end of the barrel 1. The compression member 14 is straight and is approximately as long as the reservoir A, and it is always in light contact with one side of the reservoir.

The operation of the self-feeding pen may be briefly described as follows:—When it is desired to fill the pen, the plug 15 is pushed inwardly. This movement of the plug causes the entire length of the compression member 14 to be forced in the direction of the far wall of the reservoir A, resulting in the complete deflation of the reservoir. With the reservoir in this condition, the lower end of the tube a is inserted in a body of ink, after which the plug 15 is released. As soon as the plug is released, the elasticity of the strip forces the plug outwardly and returns the compression bar 14 to its original position, permitting the reservoir to assume its original condition and the inflation of the reservoir will draw ink through the opening in the points c of the tube a, thus

filling the reservoir A. When it is desired to feed the ink through the contracted opening in the tube α , the plug 15 may be slightly pushed into the barrel 1 to bow the compressor 14 against the reservoir.

From the foregoing it will be obvious that a feeding device made in accordance with this invention may be applied to an ordinary writing pen as well as to a drafting pen.

Various changes may be made in the details of construction without departing from the spirit and scope of the invention as defined in the claim.

5. What is claimed is:—

A self-filling fountain pen comprising a barrel, a nib at one end of the barrel, a plug slidably mounted in the other end of the barrel, a compressible reservoir located within the barrel, a tube leading from the reservoir to the nib, a strip of flat spring metal located within and extending longitudinally of the barrel, said strip having its ends offset to provide attaching members and an

intermediate straight compression member, : said compression member having a length approximately equal to the length of the reservoir, and normally lying in contact with one wall of the reservoir, one of said attaching members being secured to said plug, and means securing the other attaching member to said barrel, the entire length of the compression member being moved in the direction of the opposite wall of the reservoir when the plug is forced into the barrel resulting in the complete deflation of the reservoir and the elasticity of said strip returning the compression member to its original position when the plug is released, permitting the reservoir to return to its original condition to permit the reservoir to be filled with ink.

1 in testimony whereof I affix my signature in presence of two witnesses.

JOHN H. PALMER.
